UNITED STATES PATENT OFFICE

159,663

TABLE OR THE LIKE

Leon Jackson Pattishall, Barrington, Ill.

Application January 22, 1949, Serial No. 406

Term of patent 14 years

(Cl. D33—14)

To all whom it may concern:

Be it known that I, Leon Jackson Pattishall, a citizen of the United States, residing in Barrington, in the county of Cook and State of Illinois, have invented a new, original, and ornamental Design for a Table or the like, of which the following is a specification, reference being had to the accompanying drawings, forming a part thereof.

In the drawings:

I claim:

The ornamental design for a table or the like, substantially as shown,

L. JACKSON PATTISHALL.
